MACHINE FOR TRIMMING SHOE PARTS

Eric A. Holmgren, Beverly, Mass., assignor to
United Shoe Machinery Corporation, Flemington, N. J., a corporation of New Jersey

Application November 21, 1946, Serial No. 711,239

3 Claims. (Cl. 12—67)

1

This invention relates to machines for trimming shoe parts and is illustrated herein as embodied in a welt butting and tacking machine of the type disclosed in Letters Patent of the United States No. 2,045,577, granted on June 30, 1936, on an application of Benjamin B. Blanchard.

It is an object of the invention to provide machines of the above-identified type with improved trimming mechanism adapted to sever, with a clean cut, welt materials of all kinds including welts made of plastic materials which are notorious for their toughness and resistance to cutting.

In the accomplishment of this object, the illustrated machine is provided, in accordance with one feature of the invention, with a welt butting knife having two motions, one being a motion of translation designed to carry the knife bodily into and out of operative relation to the welt to be butted, and the other being a resulting motion of the knife with relation to its carrier and designed to cause the cutting edge of the knife to move in the general direction in which it extends so as to produce a draw cut. More specifically, in the illustrated embodiment of the invention the knife is disk shaped and mounted for rotation with relation to a reciprocating carrier. The reciprocation of the carrier serves to move the knife into and out of operative position with relation to the welt. There is a link connection between the rotary disk knife and the stationary machine frame, the link connection being so constructed and arranged that, during and as a result of the reciprocation of the knife carrier, the knife is rotated with relation to the carrier.

These and other features of the invention will now be described in detail in connection with the accompanying drawings and will be pointed out in the appended claims.

In the drawings,

Fig. 1 is a front elevation of a portion of a welt butting and tacking machine in which the invention is illustrated as embodied;

Fig. 2 is a side elevation of one of the welt butting knives of the machine illustrated in Fig. 1 and associated machine parts;

Fig. 3 is a side elevation (as viewed from the line III—III of Fig. 1) of a knife operating mechanism, the parts being shown in their starting positions; and

Fig. 4 is a bottom plan (as viewed from line IV—IV of Fig. 3) of the knife operating mechanism.

The invention is illustrated as embodied in a

2

machine of the type disclosed in the above-mentioned patent and also in United States Letters Patent No. 1,709,347, granted on April 16, 1929, on an application of George Goddu and Fred L.

5 MacKenzie, and, accordingly, only such features of the general organization as it is necessary to refer to for an understanding of the invention will be described herein in detail.

As illustrated in Fig. 1, the machine has two 10 shoe supporting members 10 and a back stop 12 arranged to take the force of the cutting stroke of two welt butting knives 14 arranged to operate at opposite sides of the supported shoe at the vicinity of the heel breast line. The heel seat of 15 the shoe to be operated upon is positioned heightwise of the machine by a holdown member 16. The welt w (Fig. 2) at each side of the shoe is supported for the butting operation by a crease finder 18 (Fig. 1) an anvil 20 and a welt support 20 22. These members together with the knives 14 and a pair of tacking units 24 are mounted in a pair of swinging frames 26 fulcrumed in the machine frame to swing about vertical axes in directions extending widthwise of the shoe.

25 Each welt butting knife 14 is in the form of a disk of irregular shape, as illustrated best in Fig. 4, and has a circular cutting edge concentric to a hub portion of the knife about the axis of which the knife may be rotated, as will be described.

To cause the knife to sever the butt end of the welt with a draw cut as contrasted with the chopping cut typical of welt butting knives used heretofore in machines of the illustrated type, each 30 knife 14 of the illustrated machine has a movement of translation, as usual, but in addition thereto has a concomitant movement of rotation. To accomplish this the following mechanism for supporting and operating the knife 14 is provided, it being understood that the illustrated machine is equipped with two such knife supporting and operating mechanisms and that a description of only one of them will suffice. As 35 in the machines disclosed in the above-mentioned patents, there is provided a main slide 28 (Figs. 3 and 4) for supporting and operating the welt butting knife. Mounted on the main slide 28 for movement with relation thereto and at an angle to the direction of movement of that slide is a knife carrying slide 30 the forward end of which is provided at its lower portion with a laterally extending flange 32 (Fig. 1). Cut into the bottom face of the forward end of the knife carrying slide 30, including the flange 32, is a 40 recess 34 illustrated best in Fig. 4, the recess being 45 50 55

covered or bridged over by a bottom plate 36 secured by screws to the bottom face of the forward end of the slide 30. The bottom plate 36 has a bore to accommodate the hub of the knife 14, the hub abutting the lower face of one end portion of a link 38 located in the recess 34 and provided with a bore in alignment with the bore in the bottom plate 36 and a bore in the upper portion of the flange 32 above the recess 34.

The hub of the knife 14 is hollow and the knife 14 is countersunk in alignment with the hollow hub to accommodate a clamping screw 40 which passes through the hub of the knife 14, the bores in the bottom plate 36, the link 38 and the upper portion of the flange 32, thus mounting the knife in place, the knife being held in clamped position by a locknut 42 threaded on the end portion of the clamping screw 40 extending upwardly from the upper face of the flange 32. Thus the knife 14 and the link 38 are rigidly clamped together by the screw 40 and locknut 42, the head of the screw resting in the countersunk portion of the knife. As will be presently described, the link 38 may be rotated, thus causing a rotation of the knife 14 with relation to its carrier slide 30. To this end, the extremity of the link 38 remote from that to which the knife is clamped is apertured to surround a vertical stem 44 (Figs. 1 and 4) held in a yoke shaped arm 46 pivotally secured to a bracket 48 fixed in a casting 50 which is part of the machine frame. Thus the link 38, by sliding on the stem 44, can participate in the vertical movements of the knife 14, to be described, and can swing about the axis of the stem 44.

Referring more specifically to the knife carrying slide 30 and its movement with relation to the main slide 28, it will be noted that, as in the machines disclosed in the above mentioned patents, the main slide is provided with an inclined guideway 52 (Fig. 3) along which the knife carrying slide 30 is movable with relation to the slide 28. On movement of the knife carrying slide 30 with relation to the slide 28 the knife 14 is moved heightwise of the machine to carry it into the plane of its cutting operation or to move it out of that plane at the end of a cutting operation. To this end, the slide 30 has a lug 54 (Fig. 3) which is pivotally connected by means of a link 56 to a rotary member 58 secured to a shaft 60 mounted for rotation in the machine frame and provided with a brake mechanism (not shown here but disclosed in said patents. The brake mechanism tends to resist rotation of the shaft 60 and thus tends to resist movement of the slide 30 on movement of the slide 28. As illustrated in Fig. 3, the slide 30 is provided with an abutment 62 adapted to cooperate with a stop 64 provided on the slide 28. Moreover, the slide 28 carries a stop screw 66 the head portion of which extends into a slot 68 provided in the slide 30. As fully disclosed in the above-mentioned patents the illustrated machine is provided with mechanism for reciprocating the slide 28 in the machine frame.

As a result of the just described arrangement and on movement of the slide 28 in the direction of the arrow illustrated in Fig. 4, movement of the slide 30 with and in the same direction as the slide 28 is resisted by the described connection of the slide 30 with the shaft 60. As a result, the knife carrying slide 30 is lowered substantially vertically along the guideway 52, and thus the knife 14 is lowered into the plane of its cutting operation, this movement of the knife being

permitted by the link 38 sliding down on the stem 44. As soon as the abutment 62 engages the stop 64 the downward movement of the slide 30 ceases, the slide 30 then being moved along with the slide 28 and overcoming the resistance of the brake mechanism acting on the shaft 60. Thus, the knife 14 is moved in its plane of operation toward the supported welt and the anvil 20 with which the knife 14 cooperates in skiving off the rear end of the welt. By reason of the fact that the knife 14 is clamped to the link 38 which in turn is pivotally secured by means of the yoke shaped arm 46 to the fixed bracket 48, the knife 14, as a result of and during the just described movement of translation, is rotated about the center of its hub while the link 38 is swung from the position indicated in full lines in Fig. 4 to the phantom position indicated in the same figure. Accordingly, there is imparted to the knife, in addition to its motion of translation, a separate motion of rotation as a result of which the cutting edge of the knife is moved, so to speak, in the direction in which it extends. Therefore, when the knife engages the welt w (Fig. 2) the welt is severed by a draw cut in that the knife 14 when being moved across the end of the welt is rotated. Reverse movement of the main slide 28 at the end of the welt butting operation causes at first a relative movement between the slides 28 and 30 in that the slide 30 is merely raised along the guideway 52 since its movement with the slide 28 is again resisted by reason of the connection of the slide 30 to the shaft 60. The upward movement of the slide 30 ends when the screw 66 abuts one end of the slot 68, the knife again having been raised to its inoperative upper position. Continued movement of the main slide 28 toward the right of Figs. 3 and 4 then produces movement of the knife carrying slide 30 in the same direction as a result of which the link 38 and the knife 14 are again returned to their initial positions illustrated in Fig. 4. It will be seen therefore, that the knife has a four-way motion and that during its horizontal travel it is rotated about its own axis of rotation with the results described.

As illustrated best in Fig. 2 and as fully disclosed in the above-mentioned patents the knife carrying slide 30 is provided with a presser foot 70 mounted on a stem 72 movable in a passage-way provided in the slide 30. The presser foot 70 is adapted to engage the work just ahead of the knife and to cooperate with the knife during its cutting operation in a manner well known in the art.

Having thus described my invention, what I claim as new and desire to secure by Letters Patent of the United States is:

1. In a machine for operating on shoe parts, a fixed frame, a trimming knife, a movable carrier on which the knife is mounted for movement with relation thereto, means for actuating the carrier to impart to the knife a motion of translation along a predetermined path, and means connecting the knife to the frame and active as a result of the movement of translation of the knife to cause the knife to move with relation to the carrier without deviating from said predetermined path.

2. In a machine for operating on shoe parts, a fixed frame, a trimming knife, a reciprocating carrier on which the knife is mounted for rotation with relation thereto, means for reciprocating the carrier to move the knife bodily along a predetermined path, and means connecting the

knife to the frame and adapted to rotate the knife on reciprocation of the carrier.

3. In a machine for operating on shoe parts, a fixed frame, a disk shaped trimming knife having a rotary hub, a reciprocating carrier on which the knife is mounted for rotation with relation thereto, means for reciprocating the carrier to move the knife bodily along a predetermined path, and a link connection between the hub of the knife and the frame, the connection being active 10 as a result of the reciprocation of the carrier to rotate the knife while it moves along said predetermined path.

ERIC A. HOLMGREN.
